[57] CLAIM

The ornamental design for a temperature indicator for use on a container, as shown and described.

DESCRIPTION

FIG. 1 is a perspective view of the temperature indicator for use on a container embodying the design of the present invention, the temperature indicator's backing is shown partially removed;

FIG. 2 is a top plan view thereof;

FIG. 3 is a rear view thereof; and,

FIG. 4 is a typical side elevational view thereof, all side elevational views being identical to the side view shown in FIG. 4.

FIG. 1.

FIG. 2.

FIG. 4.

FIG. 3.
